(57) **CLAIM**

The ornamental design for an electronic locator beacon, as shown and described.

DESCRIPTION

FIG. 1 is a front perspective view of an electronic locator beacon in accordance with the new design;

FIG. 2 is a rear perspective view thereof;

FIG. 3 shows the rear perspective view of FIG. 2 with an exemplary attachment strap;

FIG. 4 is a front elevation view of an electronic locator beacon in accordance with the new design;

FIG. 5 is a rear elevation view thereof;

FIG. 6 is a side elevation view thereof;

FIG. 7 is an alternate side elevation view thereof, showing the side opposing that shown in FIG. 6;

FIG. 8 is a top elevation view thereof; and,

FIG. 9 is a bottom elevation view thereof.

The broken lines shown in the drawings are only provided to illustrate the environment of the design, and form no part of the claimed design.
